(57) **CLAIM**

The ornamental design for a light guide for narrow aperture luminaire, as shown and described.

DESCRIPTION

FIG. 1 is a front view of a first embodiment of a light guide for narrow aperture luminaire, showing our new design.

FIG. 2 is a rear view thereof;

FIG. 3 is a side view thereof;

FIG. 4 is a top view thereof;

FIG. 5 is a bottom view thereof;

FIG. 6 is a top perspective view thereof; and,

FIG. 7 is a close up view thereof of the area indicated in FIG. 6.

The broken lines in the drawings depict portions of the light guide for narrow aperture luminaire that form no part of the claimed design. The areas bounded by dash-dot broken lines form no part of the claimed design. The additional dot-dash broken lines encircling enlarged views in FIGS. 6, 7 are for annotative purposes only and form no part of the claimed design.
